UNITED STATES PATENT OFFICE.

ROY C. GREEN, OF CLEVELAND, OHIO.

LOCKING DEVICE FOR BOTTLES OR THE LIKE.

No. 924,847.

Specification of Letters Patent.

Patented June 8, 1909.

Application filed April 30, 1908. Serial No. 430,084.

To all whom it may concern:

Be it known that I, ROY C. GREEN, a citizen of the United States, resident of Cleveland, county of Cuyahoga, and State of Ohio, have invented a new and useful Improvement in Locking Devices for Bottles or the Like, of which the following is a specification, the principle of the invention being herein explained and the best mode in which

10 I have contemplated applying that principle, so as to distinguish it from other inventions.

My invention relates to means for locking bottles and their contents, umbrellas, or other articles, to a fixed or irremovable support such as a door casing or other fixed part of a house.

20 The object of the invention is to permit of such locking and release in a ready, efficient manner by simply operated means, and so as to prevent the removal of the locked article by unauthorized persons.

The said invention consists of means hereinafter fully described and particularly set forth in the claims.

25 The annexed drawing and the following description set forth in detail certain mechanism embodying my invention, the described means, however, constituting but one of various mechanical forms by means of 30 which the principle of the invention may be applied.

In said annexed drawing:—Figure 1 is a plan of the device embodying my invention which is particularly designed for the 35 securing of milk bottles, the parts of the device being therein shown in their open position. Fig. 2 is a similar plan of the device showing the parts in their closed or locked position, the housing inclosing 40 the lock being broken away to disclose the interior construction. Fig. 3 is a bottom plan of a portion of the device. Fig. 4 is a side elevation of the device, showing also a sectional portion of the support to 45 which it is attached, and also showing in dotted lines the top and neck of a bottle secured therein. Fig. 5 is a cross-section taken upon the plane indicated by the line IV—IV in Fig. 2 showing also a key in connection therewith.

50 In the device illustrated, A is the main member of the device and is formed with an angularly projecting portion a which is provided with suitable screw holes a' a' by means of which the said member may be secured to a suitable fixed or irremovable

support B. This member is formed with a curved arm a² and an arm a³. Arm a² is formed with a seat portion a⁴ formed on the arc of a circle. Upon the upper side of the 60 end of arm a³ is pivotally secured a movable member C which is formed with a semi-circular seat c. The extremity of arm C is provided with a projection c' which is formed with a lip c².

65 Upon the lower surface of the member C and projecting therefrom is a stud c³. This stud is engaged by the free end of a spring a⁵ whose other end is fixed in a slot a⁶, Fig. 3, which is formed in the end of the curved 70 member a³. The spring therefore tends to cause the member C to assume the position shown in Fig. 1, a projection a⁷ being provided to act as a stop limiting the spring-actuated movement of said member. This position 75 I designate as the "open" position of the parts.

Upon the upper side of the neck of the member A is secured the housing a⁸ which incloses a series of tumblers a⁹ pivoted upon a pin a¹⁰, Fig. 2, the whole forming a lock for member C. These tumblers are actuated to assume a normal position by small leaf springs a¹¹ suitably secured to each, their movement being limited by a stop a¹². The 80 pin a¹⁰ and the stop a¹² also form fasteners for securing the housing on the member A, as shown in Fig. 4. The outer ends of the tumblers are each provided with a hook-like portion a¹³ located adjacent to a lateral 85 opening a¹⁴ in said housing. This opening is located in the circular path of movement of the lip c² so that the latter may be caused to project therethrough when the member C is moved upon its axis and simultaneously engage all of the hook-like portions a¹³ of the tumblers, as shown in Fig. 2. The position last described of the parts and as illustrated in Fig. 2 is the "closed" position.

90 When the member C is in the last described position the seat a⁴ of the curved arm a² forms a continuation of the curved seat c of the member C and together form an inclosing seat for the neck of a bottle, the space between the free outer ends of the 95 arms a² and C being made less than the diameter of such neck, when in such position. It will therefore be seen that when a bottle is seated between these members when in the closed position it can not be removed therefrom without first unlocking the member C.

100 An upright slot a¹⁵ is formed in the side of

the housing a^8 and admits a suitable key D, Fig. 5, which may be caused to engage the tumblers and is adapted to actuate them to release the member C, as will be readily understood.

When not in use the parts are permitted to assume their open position as shown in Fig. 1 in which the member C projects into the bottle-receiving space and when it is desired to secure a bottle therein which has an enlarged top, such as illustrated, the neck of such bottle is brought into a position opposite the member C such as is shown in dotted lines in Fig. 1. A movement of the bottle inwardly will now actuate the member C to assume its closed position and cause the projection c^4 to pass through the opening a^4 , the lip c^2 pressing back the tumblers a^6 until the point thereof passes the point of the tumblers whereupon the latter snap into position and engage such lip as shown in Fig. 2 and as will be readily understood. In order to effect such operation of the parts it will be seen that the bottle must be caused to assume the position shown in dotted lines in Fig. 2. The parts of the device therefore assume their closed position and simultaneously and automatically lock the bottle in position against removal. It will be understood, of course, that the bottle-inclosing space is made of a diameter somewhat smaller than the top of the bottle so that the latter may hang without falling out.

It will be readily understood that the above described device may be used in a similar manner for securing any article which it may be desired to secure against unpremeditated removal. It will also be further understood that when it is desired to secure a bottle or other article not having an enlarged top, a suitable supporting base, (not shown) is provided which is arranged a distance vertically beneath the device such as will bring that part of the article which it is desired to clasp, in the plane of the member C, when the article is resting on such base.

I therefore distinctly claim and desire to secure by Letters Patent:—

1. In a device of the character described,

the combination of a main member provided with two arms; a pivotal member mounted upon the end of one of said arms and arranged to assume an open and a closed position and when in the latter position to form, with said main member, an inclosing seat for a bottle or the like; a lock including key-actuated tumblers and mounted upon said fixed member in proximity to the meeting point of said two arms; the one end of said pivoted member adapted to be secured by said tumblers.

2. In a device of the character described, the combination of a main member comprising a portion adapted to be affixed to a support; a neck projecting therefrom, and two arms projecting from said neck; a member pivotally mounted upon one side of and at the end of one of said arms and adapted to assume, with reference to said arms, an open and a closed position and to form a seat for a bottle or the like; a lock mounted upon said neck and upon that side of the main member upon which said pivotal member is mounted; the one end of said pivotal member being adapted to enter said lock and to be secured by said tumblers.

3. In a device of the character described, the combination of a main member including a portion adapted to be affixed to a support, and two arms projecting therefrom in opposite directions; a pivotal member mounted upon the extremity of one of said arms and adapted to assume an open and a closed position and to form an inclosing seat for a bottle or the like; a lock on said main member including key-actuated tumblers, mounted intermediately of said affixable portion and said arms, provided with a laterally located key-aperture and having an opening adjacent to the free arm of said main member; the outer extremity of said pivotal member being adapted to enter said aperture and be secured by said tumblers.

Signed by me, this 29th day of April, 1908.
ROY C. GREEN.
